FEEDING DEVICE

Adam Allendorf, Forest Hills, N. Y.

Application February 26, 1936, Serial No. 65,762

8 Claims. (Cl. 271—27)

This invention relates to a device for feeding checks or other documents or papers, one at a time, into a photographic machine or any similar machine so that a whole stack of checks will be fed through quickly, but yet only so fast as the second machine can handle them.

An object of the invention is to produce a device of this character which will feed only one check at a time so as to avoid any possibility of failure to photograph all of the checks which it is desired to so record and to produce a device which will automatically trip or put in motion the photographic machine as a check is fed into it.

Another object of the invention is to provide a novel construction which will handle checks of different sizes and handle them efficiently and expeditiously and feed them but one at a time to the recording machine.

Another object of the invention is to produce a device which can handle a stack of checks of different heights and the device illustrated and described herein, possesses a movable table to make it so adaptable.

The feeding device is small and light enough to be readily portable and is entirely self contained so that it may be readily removed if desired.

Although the particular embodiment shown and described herein is designed to cooperate with a check photographic machine, nevertheless, this invention may be used wherever it is desirable to remove papers singly from a stack or pile and convey them to another place to be introduced into another mechanism or otherwise utilized.

The device is here shown as a separate mechanism but it may readily be incorporated into a larger mechanism and derive power from a common source.

Looking at the drawings:—

Fig. 1 is a plan view of the machine.

Fig. 2 is a cross section through 2—2 of Fig. 1.

Fig. 3 is a side elevation of part of the vacuum cup actuating mechanism.

Fig. 4 is a rear elevation partly in section of the automatic trip mechanism utilized to synchronize the feeding mechanism with that class of photograph machine which requires a trip action, as each check enters the photographic mechanism.

Fig. 5 is a side elevation of part of the mechanism shown in Fig. 4.

Fig. 6 is a side elevation of the drive for the table raising mechanism.

Fig. 7 is a side elevation of part of the table raising mechanism.

Fig. 8 is a diagrammatic representation of the vacuum system.

The various elements of the feeding device are

arranged on a framework adapted to rest on the table of the photographic machine, but may be readily constructed to rest on a separate table or on the floor if this is desirable or necessary.

Looking at Fig. 2, 1 is a horizontal lower frame member of which there are two in the machine. To each of these is attached a vertical column 2 and a vertical column 3. The columns 2 are joined together at the top by an angle iron supporting member 4, and at the bottom by a similar member 5 both of which are shown in cross section. The ends of the columns 3 are likewise tied together at the top and bottom by a similar pair of angle iron frame members the lower one of which is shown in cross section at 6 but the upper one is not illustrated. These vertical and horizontal frame members form a frame for supporting the moving parts of the machine.

Mounted on this frame work is a vertically movable table shown at 7 in Fig. 1. Table 7 is adapted to slide up and down on a pair of guides shown at 8 and 9 (Figs. 1 and 2). Two sheet metal guards, one of which is shown at 10 on Fig.

2, are mounted on the frame adjacent to the two side edges of the table to serve to confine the stack of checks or other papers within the confines of the top of the table. These sheet metal guard members are bent at right angles where they are attached to the frame, so that they form guards for the back of the table, which cooperate with the two guides 8 and 9 to prevent the checks from slipping off the table and in toward the middle of the mechanism. The portions of the guards 10 which are bent in around the back of the table are shown at 11 on Fig. 1 and the top of each is bent into a horizontal plane shown at 12. A wire guard 16 adjustably retained in member 17 attached to rod 209 by set screw 18 serves to hold the papers on the table as shown in Fig. 2. Attached to the center of the back of the table, between the two guide rails, is a flexible cable, illustrated at 13, which passes upwardly and over the roller 14 and downwardly again over the winding drum 15 which is shown in detail in Fig. 7. This drum is adapted to be actuated in a step by step rotation to urge the table upwardly as the checks are fed off of the top of the stack. This mechanism and its operation will be described hereafter.

A stack of checks is illustrated on top of the table 7 at C and the top of this stack of checks is held in a more or less flat position by a pair of guide arms 24 which are adapted to engage the checks near the ends thereof.

The raising of the table is controlled by the position of a pair of feeler arms 25 which are mounted on a common projecting support 26 so as to form a Y shaped element. It is desirable to make these feeler arms of a more or less springy material. The arms are rigidly secured

to a transverse bar 30 mounted on suitable bearings 31 and 32 adjacent to the ends thereof. Bar 30 is adapted to rotate through a limited arc under the action of the arms 25 as these feeler arms are raised or lowered in accordance with the height of the stack of checks.

A bell crank lever 33 pivoted at 34 is attached by link 35 to projecting arm 36 mounted on bar 30 so that a rotational movement of the bar 30 produces a reciprocating motion of the link 35 which in turn moves the bell crank lever 33 around its pivot point. Bell crank lever 33 is made up of arm 37 to which link 35 is attached and arm 38 which is urged in a clockwise direction, as viewed in Fig. 1, by a flat spring 40 up against a stop 41. The outer end of arm 38 of the bell crank lever 33 is equipped with a series of notches or steps 42 which are adapted to cooperate with the pivoted lever 45 pivoted to the frame work at 46. Mounted on lever 45 is a pivoted pawl 47 the outer or projecting end of which is adapted to cooperate with the teeth of a ratchet wheel 49 and is normally urged into cooperation with these teeth by a coil spring 50 attached to the opposite side or end of the pivoted pawl 47. Ratchet wheel 49 is keyed to a vertical shaft 50.

The detailed construction of this table actuating mechanism is shown in Figs. 6 and 7. Shaft 50 is vertically disposed and passes down into the frame work and has at the lower end thereof a worm 51 which is journalled in a suitable bearing 52 attached to a frame member. The upper end of the shaft 50 is likewise journalled in a bearing 53 attached to one of the upper cross members of the frame. A suitable bearing to absorb the vertical thrust of this shaft is incorporated in bearing 53 but the details thereof are not illustrated. Shaft 50 is furnished with a friction connection 55 which is composed of a split cylindrical member pinned to one portion of the shaft 50 and a complementary cylindrical portion adapted to fit inside of the split portion to form a friction coupling 55 so as to furnish a friction drive to the worm 51, so that if the shaft becomes overloaded, for any reason, the friction coupling slips without breakage to any of the essential parts of the mechanism.

Worm 51 is adapted to cooperate with worm wheel 60 keyed to a horizontal shaft 61 mounted in suitable bearings on the frame members.

55 Mounted so as to rotate freely on shaft 61 is a grooved drum 15. A suitable set screw 63 in the drum 15 cooperates with a circular groove cut in the shaft 61 so as to prevent longitudinal movement of the drum 15 along the shaft but at the same time allowing the drum to rotate freely. Drum 15 is designed to wind up the cable 13 attached to the movable table 7. Power is transmitted from the shaft 61 to the drum 15 through a dog clutch 64 which is adapted to slide longitudinally on the shaft 61 a limited distance commensurate with the length of the slot 65 cut in the dog clutch 64. The pin 62 attached to the 60 shaft 61 is adapted to cooperate with the slot 65 to limit the longitudinal motion of the member 64. Clutch member 64 is equipped on the face thereof adjacent to the drum 15 with a suitable ridge or squared portion adapted to 65 operate with the slot or depressed squared portion in the end of the drum 15 to allow these two members to rotate together when the clutch member is in the position shown in Fig. 5. Normally clutch member 64 is urged toward the 70 drum 15 by coil spring 66 which is wrapped 75

around shaft 61 and positioned between the end of member 64 and a suitable collar 77 pinned to the shaft 61 by a set screw or other device.

A manual release for the clutch comprises a pivoted finger 70 pivoted to a frame member at the upper end thereof, as shown at 71, and comprising at its lower end a pair of forked arms 72 adapted to engage collar 73 on the inside thereof so that when the arm 70 is moved on its pivot point in counterclockwise direction, as viewed in Fig. 7, it tends to move the clutch member 64 to the right against the pressure of the coil spring 66. Arm 70 is manually controlled by link 75 which is normally urged to the left by a suitable coil spring 76 positioned between a portion of the frame 71 and collar 78 attached to link 75. At the outer end of the link 75 a knob 79 is attached thereto for convenient manual operation of the link 75 to disengage the table actuating mechanism.

Looking at Fig. 1, 80 illustrates a link pivotally connected to arm 45 about midway the length thereof and at its other end connected to a bell crank lever 83 pivoted at 84 to the frame work of the machine. Arm 85 of bell crank lever 83 is normally urged upwardly as shown in Fig. 1 by coil spring 86. A square rod 90 adapted to slide in a bearing member 91 is connected in a manner which will be hereafter described, to the driving mechanism of the machine so that the rod 90 reciprocates back and forth in the bearing 91. A pin 93 mounted on the rod 90 is adapted to engage the arm 85 of the bell crank 83 to move the bell crank in a clockwise direction. Upon the return motion of the shaft 90 the arm 85 is drawn back by the coil spring 86 and thus the bell crank 83 is given a rocking motion about pivot 84.

The table 7 is moved upwardly as the checks are moved from the top of the stack in the following manner:—

The oscillating movement of the bell crank 83 moves the link 80 back and forth which in turn swings the arm 45 about its pivot point and causes the pawl 47 to rotate the ratchet wheel 49 if and when the arm 45 is allowed to swing in a clockwise direction (Fig. 1) far enough to enable the pawl 47 to engage a new tooth in wheel 49. The distance that the arm 45 can move in a clockwise direction is governed by the position of the notched end 42 of the bell crank lever 33 and this position in turn is controlled by the vertical position of the pair of arms 25 which rest upon the top of the stack of checks. As the arms 25 are raised the bell crank 33 is urged in a direction to compress the spring 49 and interpose one of the notches shown at 42 to cut down or shorten the stroke of the pivoted arm 45. When the arms 25 are raised to such a position that the top of the stack of checks is at the desired level, the mechanism is so designed and constructed that the stroke of the pivoted arm 45 is shortened so that the pawl 47 will not engage a new tooth on the wheel 49 and therefore the wheel 49 will not be rotated but when the arms 25 drop, due to the fact that checks are removed from the top of the pile, the bell crank 33 is urged in a clockwise direction and the notches shown at 42 enable the arm 45 to move far enough in a clockwise direction to allow the pawl 47 to engage a new tooth on the wheel 49 and thus rotate it. Rotation of this wheel as explained before causes rotation of shaft 50, the worm and wheel, shaft 61 and finally 75

rotation of drum 15 to wind up the cable 13 and thus raise the table 7.

The manually operated link 75 serves to disengage the clutch 64 so that the table 7 may be lowered readily to accommodate a new stack of checks. This of course is done by pulling the knob 19 outwardly to disengage the clutch 64 and thus allow the drum 15 to rotate freely on the shaft 61. The upper end of shaft 50 is equipped with a hand wheel 54 to enable the shaft 50 to be rotated manually to raise the table to approximately the proper position to commence the feeding of a new stack of checks after they are positioned on the table.

Looking at Figs. 2 and 3, a movable carriage made up of side members 100 and 101 connected by cross bars 102 and 103 and equipped with four grooved wheels 104, 105, 106 and 107, is adapted to move back and forth on tracks 108 and 109. This carriage carries thereon a suitable vacuum cup for lifting the topmost check from the stack of checks and depositing it on a conveyer belt. The vacuum cup and conveyer belt will be described hereafter.

The carriage is moved by a link or pitman 110 which is pivoted to the carriage at 111 by a knurled nut 113 and connected at the other end thereof to a rotatable crank 112. Link 110 is constructed to telescope to a limited extent. The part of the link which is connected to the crank 112 has a hollow cylindrical portion shown at 114 and this is adapted to receive one end of that portion of the link which is connected to the carriage as shown at 115. Portion 115 may be moved inwardly within the portion 114 against the pressure of a small coil spring 116 and its outward motion is limited by a set screw 117 operating against a suitable shoulder on 115. The motion of the carriage to the left as viewed in Figs. 1 and 2 is limited by a set screw stop 119 which can be locked in any desired position by a lock nut 120. The telescoping construction of link 110 is to enable crank 112 to rotate freely even though the carriage has come to rest against the stop 119 before the crank 112 has reached dead center.

Crank 112 is keyed to a vertical shaft 120 which is mounted on suitable ball bearings shown at 121 and 122. Mounted on shaft 120 immediately below the crank 112 is a bevelled gear 123 adapted to mesh with bevelled gear 124 which is keyed to a horizontal shaft 125 mounted in suitable bearings shown at 126 and 127. At the outer end of shaft 125 shown near the upper right hand corner of Fig. 1 is a gear 130 adapted to mesh with a gear 131 keyed to horizontal shaft 132 which passes through the frame work from one side of the machine to the other and is mounted on suitable bearings on the frame work.

At the outer end of shaft 132 is a gear 133 which is adapted to mesh with a pinion 134 attached to a larger gear 135 both of which are mounted on a stud shaft 136. Gear 135 in turn meshes with a pinion 137 which is keyed to a shaft journalled in the frame work and passing therethrough. Upon the other end of this shaft is a belt pulley shown in dotted lines at 140. A suitable belt 141 connects pulley 140 with a pulley 142 mounted on the drive shaft of motor "M".

The operation of the carriage is as follows:— Motor "M" through belt 141 drives the reducing gears 137, 135, 134 and 133 and thus rotates cross shaft 132 upon which is mounted a pinion 131 which drives the gear 130 which in turn actuates shaft 125. The rotation of shaft 125

through bevelled gears 123 and 124 rotates the crank 112 in a clockwise direction as viewed in Fig. 1, and through the connecting link or pitman 110 the carriage is reciprocated back and forth on the tracks 108 and 109.

Keyed to shaft 125 is a bevelled gear 150 adapted to mesh with bevelled gear 151 which is keyed to a short shaft mounted in a suitable bearing 152. At the outer end of 152 is a crank 153 to which is attached a link 154 connected in turn to the square rod 90 which operates the bell crank lever 83 and through the mechanism heretofore described, lifts the table 7. The drive mechanism illustrated consists of a belt drive and a train of reduction gears as has just been described, but this drive may be modified and changed and some other type of speed reduction device may be substituted such as worm and wheel or belts and pulleys as is well known in the mechanical arts.

The movable carriage carries a vacuum cup device for transferring the checks from the table 7 to the conveyer belt which will be described hereafter. Mounted on the cross bars 102 and 103 of the carriage are a pair of right angularly disposed spaced auxiliary frame members 160 and 161 which are pinned to the members 102 and 103 as shown in Fig. 2, and which serve as supports for moving parts of the vacuum cup lift device as will be described hereinafter. A movable shaft 162 is journalled in bearings in members 160 and 161 and adapted to oscillate therein. This shaft is parallel to and disposed between the shafts or rods 102 and 103. At the outer end thereof is attached a crank arm 163 (Fig. 3) upon the outer end of which is a pulley 164 adapted to travel back and forth on a track 165 which is pivoted at 166 and the opposite end thereof whose upward motion is limited by stop 168, is adapted to be raised and lowered by link 167 the upper end of which is pivotally connected to the movable end of track 165 at 170 and the lower end is pivotally connected to sliding bar 171 at 172. Bar 171 has two slots shown at 174 and 175 through which pass bolts 176 and 177 to guide and limit the motion of the bar 171 which is adapted to move back and forth within the confines of the slots. To the end of the bar 171 is attached a link 180 which is pivotally connected at its opposite end to a bell crank lever 182 (Fig. 1). This lever is pivoted intermediate of its ends at 183 and the opposite end to which link 180 is connected, carries thereon a cam 185 having three cam surfaces 186, 187 and 188. This cam is adapted to cooperate with a cam wheel 190 shown in dotted lines, on crank 112. As the crank 112 rotates the cam wheel 190 will cause the bell crank 182 to oscillate back and forth around the pivot 183.

Coming back to the shaft 162 which is mounted on the movable carriage between the braces or rods 102 and 103, there is attached thereto the crank arm 200 with a connecting link 201 attached to arm 202 on a movable shaft 203 mounted in adjustable anti-friction bearings 204 and 205. Attached to shaft 203 near the middle thereof, is the vacuum cup supporting arm 207 which is adjustable longitudinally by telescoping one section inside of another and locking them together with set screws, shown at 208 and 209. The outer end of arm 207 is forked as shown at 210 to pivotally receive the vacuum cup 211 which is made of a flexible rubber cup 212 attached to a metal body from which leads the vacuum pipe 213.

The operation of the carriage is as follows:— Motor "M" through belt 141 drives the reducing gears 137, 135, 134 and 133 and thus rotates cross shaft 132 upon which is mounted a pinion 131 which drives the gear 130 which in turn actuates shaft 125. The rotation of shaft 125

A flat coil spring made up of two leaves and attached to frame rod 209 at 210, as illustrated, is made up of a bow-shaped leaf 212 and a leaf 213 which rests thereon and the end of which is adapted to cooperate with arm 202 to urge the vacuum cup downwardly when the carriage is near the end of its stroke adjacent to the stop 119.

The small coil spring 215 is attached to the movable end of the track 165 and to the sliding bar 171 so as to tend to return the track 165 to its more or less horizontal position, after it has been moved downwardly by the action of the bar 171 and link 167.

15 Pipe 213 leading from the vacuum cup 211 leads back along the mechanism to the vacuum pump "P" made up of an open ended cylinder 214, piston 215, piston rod 216 and a crank 217 attached to shaft 120. (Diagrammatic view is shown in 20 Fig. 8.)

In operation the vacuum cup works as follows:—

As the movable carriage approaches the position shown in the figures, continued rotation of 25 the crank 112 in a clockwise direction will bring the carriage back against the stop 119 and the spring 212 will act to force the vacuum cup 212 downwardly. At the same time, cam wheel 190 will have cooperated with the cam surfaces on 30 the cam 185 to move the bell crank lever in a clockwise direction and thus slide the bar 171 toward the right as viewed in Figs. 1, 2 and 3. This will cause the lower end of the link 167 to move to the right and the movable end of the 35 track 165 will move downwardly. As the track is lowered, arm 163 will move downwardly and rotate shaft 162 through a small arc and thus through the link 201 move the vacuum cup arm 207 downwardly until the vacuum cup engages the 40 topmost check on the pile of checks on table 7. The pivotal mounting of the vacuum cup on the forked ends 210 of the arm 207 will enable the cup to accommodate itself to the angle of the surface of the check.

45 The vacuum pump "P" is synchronized with the carriage because they are both driven from a common shaft 120. The crank of the pump is so positioned that the piston 215 of the pump begins its suction stroke just before the vacuum cup starts downwardly to engage the check so that when the cup engages the check a vacuum exists sufficient to lift the check from the pile.

Continued rotation of the crank 112 past its 50 dead center will bring the cam wheel 190 into engagement with the cam surface 188 and the bell crank lever 192 will return toward the position shown in the drawings, which will enable the coil spring 215 to raise the track 165 and thus raise the vacuum cup through the connecting 55 linkage which has already been described. The vacuum cup will lift a check with it and upon further rotation of the crank 112 the carriage carrying the vacuum cup and check will be moved to the right as viewed in the Figs. 1 and 2 and 60 the check will be carried into engagement with the conveying portion of the mechanism which will carry it to the outlet of the device. As the carriage reaches the opposite end of its stroke, from that shown in the figures, the check will 65 be in position to be removed from the vacuum cup and this is readily accomplished because the vacuum pump "P" has completed its suction stroke and before this point commences its pressure stroke, so that the check is released by the 70 vacuum cup when the carriage is just about at 75

the end of its stroke opposite to its position shown in the figures.

A pair of flat weighted fingers 24 are pivotally connected to rod 209 and so positioned that they rest on the checks near the ends thereof to compensate for the pressure of arm 25 near the center of the check and thus maintain the checks in a more or less flat position.

As the check is lifted from its resting place on the pile by the vacuum cup 211 it moves upwardly 10 as viewed in Fig. 2 and passes between the turned over edges 12 of the guards 10 and the arms 24 and then it moves to the right as viewed in the figures and the edge thereof passes under springs 220 and 221 which are secured to cross bracket member 223 by suitable screws 224 and 225. The other end of these flat leaf springs are curved 15 upwardly a little bit to more readily allow the edge of the checks to pass thereunder and they bear down upon two wedge shaped rubber feet 20 230 and 231 which are adapted to prevent any more than one check passing onto the conveyer belt at a time. If by chance the vacuum cup should pick up two checks the lowermost one will be stopped by the rubber feet whereas the top- 25 most one will continue through under the springs 220 and 221 onto the conveyer belt. The supporting bracket of which member 223 is a part, is attached to the frame at the other end thereof by bolt 233. A pair of eyes 235 and 236 are 30 turned up from the main body of this bracket shown at 234 and a supporting rod 237 is adapted to pass through the eyes and is supported at its ends on the frame at 238 and 239. The supporting bracket carries a centrally disposed guide 35 finger 240.

A conveyer belt 250 passes over pulleys 251, 252 and 253. Pulley 252 is mounted on a shaft 254' shown in Fig. 1, to which is keyed gear 260^a which is in mesh with gear 261' on drive shaft 40 132. A similar conveyer belt 249 passes over a similar set of pulleys so that the device is equipped with a pair of flat conveyer belts.

Cooperating with the conveyer belts 250 and 249 are two pairs of round belts. A horizontal 45 pair is shown in Fig. 1 at 254 and 255. Belt 254 passes over pulley 257 mounted on an arm 258 which is supported by the supporting bracket heretofore described. Arms 258 and 259 (which carry pulley 260) can be conveniently made of 50 one piece bent over as shown in Fig. 1. Pulley 263 carries round belt 255 which is similar to belt 254 and cooperates with flat belt 249. The two supporting arms forming one piece can be pivotally or freely supported on the supporting 55 bracket of which 234 is the main element. Belts 254 and 255 pass over pulleys cut on roller 260' which is journaled in bearings at 261 and 262. Bearings 261 and 262 are mounted on two flat 60 springs 265 and 266 which are rigidly secured at 267 and 268 to the frame work and which tend to force the roller 260 downwardly so that the belts thereon will cooperate with the conveyer belts. The second pair of round belts shown at 270 and 271 also pass over grooves cut in roller 260 and 65 around a pair of pulleys, one of which is shown at 273 in Fig. 2.

Pulley 273 and the similar pulley which carries belt 279 are mounted on shaft 285 which is attached to members 286 pivoted to the frame 70 work at 287 so that shaft 285 is free to pivot about point 287 and thus compensate for various thicknesses of checks which have to pass between the round belts 270, 271 and the flat conveyer belts 250 and 251. In actual operation both pair 75

of round belts, that is, 254 and 255, 270 and 271, are forced into contact with the conveyer belt 250 (for clarity in the drawings, belt 254 is shown in Fig. 2 spaced from belt 250). The round belts 5 are kept in operation because of the frictional contact with the flat conveyer belts which are power driven as heretofore described.

A supporting table shown at 280 in Fig. 2, and which occupies the full width of the machine is 10 secured to the angle frame work at one end (left end as viewed in Fig. 2) and supported by two adjustable supports (only one of which is shown at 282) adapted to pass through the holes in the 15 table and susceptible of vertical adjustment by knurled nuts, one of which is shown at 283. This table serves to support the conveyer belts and keep them flat and also to support that portion 20 of the check which is not riding on the belts.

In operation after the check is lifted by the 25 vacuum cup 211 and moved forward under the spring fingers 220 and 221 the edge thereof is engaged by the conveyer belts 249 and 250 and the round belts 254 and 255 and the check travels along the conveyer belt from left to right as 30 viewed in Fig. 2 and thus is picked up by round belts 270 and 271 in cooperation with the sloping portion of belts 249 and 250 and carried down to the outlet of the feeding device which is positioned immediately above the inlet of the photographic machine.

In some types of check photographing machines it is necessary to trip the machine as each check is delivered to it. In order to accomplish this automatically, I have devised a trip mechanism 35 which will operate in synchronism with the rest of the feeding device to automatically trip the photographic machine after each check is delivered to it. This device is shown in detail in Figs. 4 and 5. It comprises a vacuum motor with 40 a cylinder 300 closed at both ends, a piston 301 and a piston rod 302. The upper end of the cylinder as viewed in this figure, is connected by a pipe 303 to valve 304 (Figs. 1 and 8) which serves to connect or disconnect this vacuum 45 motor and thus enable the operator to utilize the trip mechanism or not, depending upon the type of photographic machine he is working with. When valve 304 is open and pipe 303 is connected to pipe 213 which leads from the vacuum pump, 50 the trip mechanism will operate. Surrounding piston rod 302 is a coil spring 306 which is compressed between the end of cylinder 300 and a collar 307 pinned to shaft 302 so as to normally tend to move the piston 301 downwardly as 55 viewed in Fig. 4. Piston rod 302 is drilled at the lower end thereof so as to slidably receive the end of lever 309 shown in dotted lines which lever is attached to a rocker shaft shown at 310. The opposite end of this lever 309 from the end 60 which cooperates with piston rod 302 has an up-standing lug thereon 312 to which is attached a coil spring 313 which coil spring tends to move the lever 309 and shaft 310 in a clockwise direction. One end of coil spring 313 is attached to 65 an adjustable rod 315 which has a knurled nut 316 to supply adjustment for the coil spring.

On rotatable shaft 310 is mounted a crank or lever 311 which is connected by link 314 to a collar 316 mounted on a cylindrical screw 317 threaded on a rod 318 which is connected by a universal joint to sliding rod 319 which slides in a bearing 320 located in curved supporting arm 321 which has a curved slot therein through which pass screws 322 and 323 which are adapted to 70 screw into an arm 324 attached to the frame

work of the machine. By means of the screws 322 and 323 the position of the end of rod 319 may be adjusted within certain limits to position the end thereof which is equipped with a rubber end piece 326. A coil spring 321 is located between the arm 321 and a collar 328 attached to rod 319 so as to normally tend to move the rod 319 upwardly as shown in Figs. 4 and 5. Link 314 is equipped with a Z shaped finger 330 the function of which will be hereinafter explained. 10

The rod 90 shown in Figs. 1 and 3, as previously explained, is given a reciprocating motion by link 154 attached to crank 153. To the end of this rod is pivoted a link 335 which is connected to a pivot lever 336 pivoted at 337. 15 At the opposite end of 333 at the end of which link 335 is connected, is a pin 340.

Fig. 5 also shows some of the elements of that type of check photographing machine which requires manual operation of a starting lever upon 20 the insertion of each check. It is with this type of machine that the trip lever is used. The hinged portion of the tray of the photographing machine is illustrated at 370. It is pivoted on hinge 371, which is attached to the stationary 25 part of the tray, part of which is shown at 372. On the underside of the tray is a stationary arm, 373, to which is pivotally secured a rod 374, which in turn is connected to the starting mechanism 30 of the photographing machine. A cooperating 35 guide to assist the operator in inserting the checks is shown at 375, and the belt adapted to receive the checks is illustrated at 376, running on pulley 377. A roller, 378, is adapted to cooperate with the belt to convey the check to the 40 photographing portion of the mechanism. When the movable portion of the tray is moved downwardly, the photographing mechanism is put in operation. With the manual feeding, this is accomplished by the hand of the operator when he 45 inserts the check on the conveying belt. With mechanical feeding of the checks by the applicant's device, the movable portion of the tray, 370, is moved downwardly by the rod or trip, 319.

In operation when it is desired to utilize the 45 trip mechanism, the valve 304 is opened so as to connect pipe 303 with the vacuum pump. When the inlet to the vacuum cup is open i. e. not obstructed by the presence of a check, the vacuum produced in pipe 303 by the pump "P" is insufficient to move the piston 301 against the springs 306 and 313 with the result that although the 50 vacuum pump may be on a suction stroke, the trip vacuum motor will not operate until the vacuum cup picks up a check and thus stops the 55 inflow of air through pipe 213. When this happens the vacuum inside the pipe 303 increases and becomes strong enough to move the piston 301 upwardly which rotates levers 309 and 311 in an anticlockwise direction thus moving the 60 link 314 to the right as viewed in Fig. 4.

In the meantime, rod 90 has been moving back and forth as previously described, with the result that lever 336 is oscillated about its pivot point 337 and pin 340 raises and lowers and as the 65 member 330 and link 314 moves over to the right the former hooks the pin 340 and the link 314 which is connected to rod 319, will move downwardly with the pin 340 and thus move the rod 319 downwardly to actuate and trip the mechanism on the photographic machine. 70

The various elements of the mechanism are so proportioned and designed that at about the time pin 340 reaches its lowermost position, the pump "P" has begun to reverse its stroke and the 75

- vacuum in the pipe 303 is reduced sufficiently so that the springs 306 and 313 will move the piston 301 upwardly to its original position and thus move the link 314 with the hook 330 thereon to the left and thus disengage it from the pin 340 so that the coil spring 327 will return the plunger or rod 319 and the mechanism connected thereto to the original position shown in Fig. 3.
- 10 The top of the stack of checks shown on the table 7 is illustrated as being slightly lower than it is maintained in actual operation so that the elements of the machine immediately above the top check can be more clearly illustrated. The 15 horizontally disposed round belts which are adapted to cooperate with the horizontal portions of the flat belts are shown spaced from the flat belts for convenience of illustration, whereas in actual operation they contact each other.
- 20 It is of course understood that the specific description of the structure set forth above may be departed from without departing from the spirit of my invention as set forth in this specification and the appended claims.
- 25 Having now described my invention, I claim:
1. In a device of the character described, a vertically movable table adapted to carry a stack of papers such as checks, bills, notes or the like, a conveyer belt mechanism, a vacuum means for lifting a piece of paper from said table, and transferring it to said belt mechanism and a trip lever and positive mechanical means for actuating it when said vacuum means picks up a paper from said table.
  - 35 2. In a device of the character described, a vertically movable table for holding a stack of papers such as checks, bills or the like, a conveyer belt for moving said pieces of paper through the machine to the outlet thereof, a vacuum lifting device for transferring a paper from said table to said belt and means interposed between said vacuum lifting device and said conveyer belt comprising a pair of spring fingers resting on friction elements and so designed that the paper carried by said vacuum device must pass edgeways therebetween before reaching said conveyer belt.
  - 40 3. In a device of the character described, a vertically movable table for holding a stack of papers, such as checks, bills or the like, a conveyer belt for moving said pieces of paper through the machine to the outlet thereof, a vacuum lifting device for transferring a paper from said table to said belt and means for separating all but the topmost papers from the vacuum lifting device comprising two surfaces through which said papers must pass edgewise, a smooth non-friction upper surface and a lower friction surface so designed and arranged as to press lightly together and to receive the edge of the paper or papers attached to said vacuum lifting device therebetween before said paper or papers reach the conveyer belt.
  - 45 4. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever adapted to actuate the starting control of a check photographing machine, a positively driven reciprocating element, means for connecting said trip lever and reciprocating element to actuate the former, and means for actuating said connecting means when and only when said vacuum cup engages a piece of paper to transfer it from said stack to said conveyer belt.
  - 50 5. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever adapted to actuate the starting control of a check photographing machine, a positively driven reciprocating element, means for connecting said trip lever and reciprocating element to actuate the former, and means for actuating said connecting means when and only when said vacuum cup engages a piece of paper to transfer it from said stack to said conveyer belt.
  - 55 6. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever adapted to actuate the starting mechanism of a check photographing machine, a positively driven element, means for connecting and disconnecting said trip lever and positively driven element and means for operating said first-mentioned means to connect said element and trip lever only when said vacuum cup engages a piece of paper to lift it from said stack to said conveyer belt.
  - 60 7. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever adapted to actuate the starting mechanism of a check photographing machine, a positively driven element, means for connecting and disconnecting said trip lever and element, and a vacuum motor for operating said connecting means to connect said trip lever and driven element to operate the former only when said vacuum cup engages a piece of paper to lift it from said stack to said conveyer belt.
  - 65 8. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever adapted to actuate the starting mechanism of a check photographing machine, a positively driven element, means for connecting and disconnecting said trip lever and element, and a vacuum motor connected to said vacuum pump and cup and adapted to actuate said connecting means only when the opening in the vacuum cup is closed by a piece of paper so that a relatively high vacuum is produced inside the vacuum motor, thus enabling it to actuate the connecting mechanism to connect the positively driven element and the trip lever so that the latter will operate to start the check photographing machine.

reciprocating element and means for connecting said trip lever and reciprocating element to actuate the former.

5 5. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever 10 adapted to actuate the starting control of a check photographing machine, a positively driven reciprocating element, means for connecting said trip lever and reciprocating element to actuate the former, and means for actuating said connecting 15 means when and only when said vacuum cup engages a piece of paper to transfer it from said stack to said conveyer belt.

6. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever 20 adapted to actuate the starting mechanism of a check photographing machine, a positively driven element, means for connecting and disconnecting said trip lever and positively driven element and means for operating said first-mentioned 25 means to connect said element and trip lever only when said vacuum cup engages a piece of paper to lift it from said stack to said conveyer belt.

7. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever adapted to actuate the starting mechanism of a check photographing machine, a positively driven element, means for connecting and disconnecting said trip lever and element, and a vacuum motor for operating said connecting 40 means to connect said trip lever and driven element to operate the former only when said vacuum cup engages a piece of paper to lift it from said stack to said conveyer belt.

8. In a device of the character described, a table adapted to support a stack of papers such as checks, bills or the like, a conveyer belt to transfer said papers to the outlet of said machine, a vacuum cup to lift the topmost paper from the stack and move it on to the conveyer belt, a vacuum pump connected to said cup, a trip lever adapted to actuate the starting mechanism of a check photographing machine, a positively driven element, means for connecting and disconnecting said trip lever and element, and a vacuum motor connected to said vacuum pump and cup and adapted to actuate said connecting means only when the opening in the vacuum cup is closed by a piece of paper so that a relatively high vacuum is produced inside the vacuum motor, thus enabling it to actuate the connecting mechanism to connect the positively driven element and the trip lever so that the latter will operate to start the check photographing machine.

ADAM ALLENDORF.
